PRODUCTION OF ALCOHOLS

Floyd J. Metzger, New York, N. Y., assignor to
 Air Reduction Company, Incorporated, New
 York, N. Y., a corporation of New York

Application December 4, 1936, Serial No. 114,285

4 Claims. (Cl. 260—156)

This invention relates to improvements in the synthetic production of alcohols from alkylene hydrocarbons with the use of a sulfuric or phosphoric acid catalyst maintained at a high temperature and pressure and with the use of a lead lined apparatus for carrying out such process.

This application is in part a continuation of my prior application Serial No. 747,682 filed October 10, 1934.

In the catalytic production of alcohols from alkylene hydrocarbons, particularly the production of ethyl alcohol from ethylene, with the use of a dilute sulfuric or phosphoric acid catalyst, in a continuous manner, the temperature required for carrying out the process in a satisfactory manner may be around 250° C. or 275° C. or even 300° C. or higher, and the dilute acid must be maintained at such high temperature and under a high pressure during the continuous carrying out of the process.

Sulfuric or phosphoric acid, if brought into contact with a lead lining at such high temperatures, will rapidly corrode or destroy the lead lining which will not withstand the corrosive action of such acids at such high temperatures.

I have found that the production of alcohol can be satisfactorily carried out in a lead lined apparatus at such high temperatures by providing an insulating layer of acid resistant material of sufficient thickness between the acid and the lead lining and by cooling the lead lining so that it is maintained below the critical temperature at which such objectionable corrosion by the acid takes place. I have found that, in the carrying out of such a process, using dilute sulfuric acid as a catalyst, the critical temperature of the lead, up to which it can stand the action of the sulfuric acid, is around 200 to 220° C., and that with phosphoric acid, the critical temperature of the lead is about the same, or somewhat lower than this, and that, by keeping the lead lining safely below such critical temperature, by maintaining a regulated temperature differential between the lead lining and the acid in the apparatus, the acid can be readily maintained at much higher temperatures than the critical temperature, e. g. around 250° C. or 275° C. or even 300° C. or higher, without injury to the lead lining during the carrying out of the process.

The insulating layer of acid resisting material should be of sufficient thickness to enable the necessary temperature differential to be maintained. It is not necessary that the acid resisting lining should be impermeable to the acid,

and the acid which passes through the lining, or, where the lining is made of bricks or blocks, through the joints between the bricks or blocks, or through the cement in which the bricks or blocks are set, will come into contact with the lead lining. The acid resisting lining should, however, be such as to prevent circulation of the acid over the lead lining. That is, the acid resisting lining should be of sufficient thickness to give the necessary temperature insulation and enable the necessary temperature differential to be obtained and it should be free from cracks or openings of such nature as to permit the hot acid to circulate over the lead lining in a manner such that it is not protected.

Various types of materials may be used for the acid resisting insulating lining which is provided inside of the lead lining. Any material selected for this lining should, of course, be resistant to the acid which is used, that is, to phosphoric acid or to sulfuric acid as the case may be, and should be a sufficiently good insulator or used in sufficient thickness to provide the necessary temperature differential between the hot acid and the lead lining. Bricks of Pyrex glass are advantageous for use with either phosphoric or sulfuric acid. These bricks are available in accurately machined form, so that they may be set in place without the use of cement with sufficiently tight joints so that there is no circulation of acid between the bricks such as might permit objectionable corrosion of the lead lining by the washing action of the circulating acid. Another material which may be used with advantage with either sulfuric or phosphoric acid is a variety of porcelain known in the trade as "Isolantite." With sulfuric acid, acid resisting brick, such as a high grade of silica brick, set in acid resisting cement, may be used with advantage. Other suitable acid resisting lining materials may also be used.

The catalytic production of ethyl alcohol by the catalytic interaction of ethylene and steam in the presence of hot, dilute acid is an exothermic reaction, which can be regulated and controlled by regulating the temperature of the steam and ethylene entering the converter chamber or by neutralizing the heat of reaction by the addition of a regulated amount of water or by permitting any excess of heat of reaction to escape through the walls of the apparatus. Whatever the method of regulation of the temperature of the acid in the converter, it is necessary both to keep this acid at a sufficiently high temperature to bring about in an

effective manner the conversion of the ethylene into ethyl alcohol and also to prevent undue rise of temperature due to the exothermic reaction.

5 In a converter chamber having a steel shell with a lead lining and with an insulating layer of acid resisting material inside the lead lining, the necessary temperature differential between that of the acid inside the converter chamber 10 and the lead lining should be maintained to protect the lead lining, that is, to maintain it safely below the critical temperature. The extent to which the lead lining can be cooled below the critical temperature will be limited by the fact 15 that excessive cooling may cool the acid too much, and while the lead lining should be maintained at a safe margin below its critical temperature, it should not be maintained at such a low temperature as will interfere with the maintenance of the necessary high temperature of the acid required for the carrying out of the process.

Instead of providing all the insulation on the outside of the steel shell, I provide only such an 25 amount of insulation at this location as will avoid undue cooling of the converter as a whole and of the acid contained therein, relying on the insulating lining within the converter for a part of the heat insulation and to obtain the necessary temperature differential, and supplying 30 only such added insulation outside the steel shell as is required to maintain the apparatus at a proper temperature. The thickness of the outside insulation can be readily adjusted to 35 permit the proper amount of cooling but to avoid objectionable cooling.

The invention will be further described in connection with the accompanying drawing, which shows in a conventional and diagrammatic manner 40 an apparatus embodying the invention and adapted for the practice of the process of the invention.

In the drawing, Fig. 1 is a flow sheet showing the different parts of an apparatus for the 45 production of alcohols from alkylene hydrocarbons; and,

Fig. 2 is an elevation partly in section of the converter.

In the diagrammatic arrangement of Fig. 1, 50 the fresh supply of olefin gas, such as ethylene, is supplied under the necessary high pressure through the pipe 1, past the regulating valve 2, and is admixed at 3 with the recycled ethylene, which is further admixed at 4 with water in 55 proper proportion and the ethylene and water then passed to the heat exchanger 5, heated by the outgoing hot gases and vapors, and with resulting conversion of the water into steam and preheating of the steam and ethylene mixture, 60 which is further heated in the superheater 6, for example, by hot diphenyl oxide. The preheated steam and ethylene in suitable proportions are then passed to the converter 8, filled part full with dilute sulfuric or phosphoric acid, which, 65 at the high temperature and pressure, acts as a catalyst to convert part of the ethylene and steam to alcohol. The admixed alcohol vapors, steam and unconverted ethylene pass from the converter 8 through the line 9 to the heat 70 interchanger 5, where they are cooled and partly condensed, and then to the first condenser 15. The condensed aqueous alcohol collects in the separator 16 and can be drawn off through the line 17, having pressure reducing valve 18 there- 75 in, to the storage tank 19. The uncondensed

vapors and ethylene pass through the line 20 to the second condenser 21 and thence to the receiver 22, where the further amount of condensed aqueous alcohol is separated and drawn off through the line 23 to the storage tank 24. 5 The remaining ethylene is then returned by the line 25 and pump 26 for admixture at 3 with the fresh ethylene.

The diagrammatic arrangement thus described is intended to be illustrative of the carrying out of the process, but the process is not limited to the details and specific arrangements shown and described.

The converter 8, as shown in Fig. 2, has an outer steel shell 30 of a construction adapted to 15 withstand high pressure, e. g. of 1000 pounds per square inch or higher. Within this steel shell is the lead lining 31; and inside this lead lining is the insulating layer of acid-resisting material 32, which may be made of Pyrex glass bricks, 20 acid resisting brick set in acid-resisting cement, etc.

The converter chamber is shown with supports 33 at the bottom and with a bolted head 34 at the top having openings 35 and 36 there- 25 through for the introduction of the admixed ethylene and steam and for the escape of the unconverted ethylene and steam and admixed alcohol vapors.

The converter is shown as provided with a perforated distributing plate 38 below which the admixed steam and ethylene enter, and suitable filling material 39, such as Raschig rings or cylinders of the same length and diameter and of acid resisting material is shown as supported on 35 said perforated plate to bring about intimate contact of the ethylene and admixed steam with the body of dilute acid as they pass upwardly through the converter.

A thin layer of insulation 37 is shown on the 40 outside of the steel shell, the thickness of this insulation being regulated to give the proper protection to the apparatus from undue cooling while nevertheless permitting sufficient cooling to insure maintenance of the lead lining sufficiently 45 below the critical temperature above referred to.

Insulation applied to the outside of the apparatus is readily accessible and may be of a character which permits increase or decrease of its amount in order to decrease the total heat loss 50 or leak of the apparatus to a minimum while simultaneously maintaining the proper temperature gradient between the inside and outside of the container, that is, between the high temperature acid inside the converter and the lead 55 lining adjacent the steel shell.

In the continuous production of ethyl alcohol from ethylene different strengths of sulfuric or phosphoric acid can be used. With the higher temperatures, e. g., around 250° C. or higher, relatively dilute sulfuric or phosphoric acid is advantageously used, generally below 50% strength, and even down to a small percentage. With such dilute acids high temperatures, such as those referred to, are advantageous, and the present invention enables such temperatures to be advantageously employed while at the same time protecting the apparatus from leakage by a lead lining which is itself protected from corrosion by the maintenance of the temperature gradient 70 above referred to.

The pressure maintained during the process, with such dilute acid, is a relatively high pressure which may be as high as 1000 pounds per square inch or higher.

The proportions of steam and ethylene or other olefin will vary depending upon the temperature, pressure and acid concentration, these various factors being interdependent.

- 5 It will thus be seen that the present invention provides an improved method of producing alcohols by the catalytic hydration of olefins with the use of dilute sulfuric or phosphoric acid catalysts maintained at a temperature above the critical 10 temperature which a lead lined converter can withstand while a lead lining is nevertheless used and protected from such corrosion by the use of insulating material and the maintenance of a temperature gradient between the hot acid 15 and the lead lining such that the lead lining is maintained safely below the critical temperature.

I claim:

1. The method of producing alcohols in a continuous manner by the catalytic hydration of 20 olefins with a dilute acid catalyst of the class consisting of sulfuric and phosphoric acids, which comprises maintaining a body of such dilute acid catalyst, during the catalytic hydration of the olefins, of substantially uniform strength and 25 under a high pressure in a high pressure converter having a lead lining, maintaining the body of dilute acid catalyst at an active catalytic temperature far above the normal boiling point of the dilute acid and above the temperature to 30 which the lead lining can be subjected without objectionable corrosion, insulating the body of acid from the lining and maintaining the lining at a temperature below that of objectionable corrosion, and subjecting the lining to regulated 35 cooling to aid in the maintenance of the high temperature of the body of acid catalyst and the said temperature differential.
2. The method of producing alcohols in a continuous manner by the catalytic hydration of 40 olefins with a dilute acid catalyst of the class consisting of sulfuric and phosphoric acids, which comprises maintaining a body of such dilute acid of less than about 50% strength under a high pressure in a high pressure converter having a lead lining, maintaining the body of dilute acid catalyst at an active catalytic temperature in excess of about 220° C. during the catalytic hydration of the olefins, said temperature being far above the normal boiling point of the dilute 45 acid and above the temperature to which the lead lining can be subjected without objectionable corrosion, insulating the body of acid from the lining and maintaining the lining at a temperature lower than about 200° C. and below 50 that of objectionable corrosion of the lining by the acid, and subjecting the lining to regulated cooling to aid in the maintenance of the high temperature of the body of acid catalyst and the said temperature differential.
- 55

3. The method of producing alcohols in a continuous manner by the catalytic hydration of olefins with a dilute acid catalyst of the class consisting of sulfuric and phosphoric acids, which comprises maintaining a body of such dilute acid catalyst, during the catalytic hydration of the olefins, of substantially uniform strength and under a high pressure in a high pressure converter having a lead lining, maintaining the body of dilute acid catalyst at an active catalytic 10 temperature far above the normal boiling point of the dilute acid and above the temperature to which the lead lining can be subjected without objectionable corrosion, insulating the body of acid from the lining and maintaining the lining 15 at a temperature below that of objectionable corrosion, and subjecting the lining to regulated cooling to aid in the maintenance of the high temperature of the body of acid catalyst and the said temperature differential, said regulated cooling being effected by insulating the lining from the surrounding atmosphere, the nature and thickness of said insulation being such as to maintain said temperature differential between the hot acid catalyst and the lining, and between 20 the lining and the atmosphere during the process.

4. The method of producing alcohols in a continuous manner by the catalytic hydration of 30 olefins with a dilute acid catalyst of the class consisting of sulfuric and phosphoric acids, which comprises maintaining a body of such dilute acid catalyst of substantially uniform strength under a high pressure in a high pressure converter having a metal shell adapted to withstand high pressure and a lead lining therein, maintaining the body of dilute acid, during the catalytic hydration of the olefins, at an active catalytic temperature in excess of about 200° C., said temperature being far above the normal boiling point of the 40 dilute acid and above the temperature to which the lining can be subjected without objectionable corrosion, insulating the body of hot acid from the lining and maintaining the lining at a temperature lower than about 200° C. and below 45 that of objectionable corrosion of the lining by the acid, and subjecting the lining to regulated cooling to aid in the maintenance of the high temperature of the body of acid catalyst and the said temperature differential, said regulated cooling being effected by insulating the lining from the surrounding atmosphere, the nature and thickness of said insulation being such as to maintain said temperature differential between the hot acid catalyst and the lining, and between 50 the lining and the atmosphere during the process.
